CLAIM

The ornamental design for a hair clip, as shown and described.

DESCRIPTION

FIG. 1 is a perspective view of a hair clip;

FIG. 2 is a front view of the hair clip of FIG. 1;

FIG. 3 is a rear view of the hair clip of FIG. 1;

FIG. 4 is a right side view of the hair clip of FIG. 1;

FIG. 5 is a left side view of the hair clip of FIG. 1;

FIG. 6 is a top view of the hair clip of FIG. 1; and,

FIG. 7 is a bottom view of the hair clip of FIG. 1.

In the drawings, the broken lines illustrate portions of the hair clip that form no part of the claimed design.
